UNITED STATES PATENT OFFICE

PAUL J. SCHWARZHAUPT, OF SCOTIA, NEW YORK, ASSIGNOR TO GENERAL ELECTRIC COMPANY, A CORPORATION OF NEW YORK

PHONOGRAPH RECORD DISK

Application filed January 18, 1930. Serial No. 421,836.

My invention relates to phonograph record disks and particularly to record disks which are of such a nature that for playing the records thereon it is desirable to employ a form of needle other than that usually found with ordinary household phonographs. An example of such a record disk is that on which a person may record a spoken message and transmit it through the mail to one who, upon receiving the record, has only to play it in the usual manner on his own phonograph to hear the message. Such record disks have been successfully made of a paper base covered with a lacquer in which the record groove is cut. It has been found, however, that in certain cases when such records were played using the sharp pointed steel needles commonly employed with household phonographs, the records sustained excessive wear but that with a needle having a more rounded point the life of the record was greatly prolonged. Hence it becomes desirable to furnish the person receiving such a record with a playing needle which is better adapted for playing the record than those which he is likely to have on hand. It is the object of my invention, therefore, to provide an improved phonograph record which carries with it a playing needle which is particularly adapted for use in playing the record which it accompanies.

My invention will be better understood from the following description taken in connection with the accompanying drawings, and its scope will be pointed out in the appended claims.

Referring to the drawings, Fig. 1 shows a record disk having a playing needle secured therein and Fig. 2 is a fragmentary cross sectional view drawn to a larger scale of the part of the disk containing the needle.

In Fig. 1, I have shown the record disk 1 as one bearing a sound record 2. It may, however, be a blank disk upon which the sound record is to be made. It is shown as having a triangular hole 3 in the center adapting it to fit over a similarly shaped center stud 50 on the recording machine, the hole being of

such a size that the disk will just fit over the round turntable stud of the ordinary phonograph.

In that portion of the disk between the center hole and the record zone the disk is provided with an opening of a size adapted to receive a playing needle such as is commonly used for playing disk records. The needle opening may be made in various ways, for example, where the record has a paper base and is blanked out of a large sheet the opening for the needle may be made at the same time that the disk is blanked and the opening 3 is punched. A special needle or stylus 4 having the form of point which especially adapts the needle for the playing of this record is embedded in the record disk by inserting it in the aforesaid opening. The needle may make a sufficiently tight fit in the opening that it will not be lost out during transportation of the record but I prefer to insure its retention in the disk by the use of some hardening liquid as shown at 5 which, for example, may be a drop or two of the lacquer which forms the record surface of the disk. The person receiving the record has only to push out the needle using any suitable means at hand such as a pencil or jack knife and in accordance with the directions on the record use it for the playing of the record on his own phonograph. The use of a small quantity of hardening liquid such as lacquer to hold the needle in place also serves to protect the needle from moisture, thus preventing possible rusting of the needle before it is used.

What I claim as new and desire to secure by Letters Patent of the United States, is:

1. A phonograph record disk having embedded therein a needle adapted for use in playing the record.
2. A phonograph record disk having a slot formed therein and a needle adapted for use in playing the record held in said slot.
3. A phonograph record disk having a playing needle embedded in a portion thereof not occupied by the record grooves.
4. A phonograph record disk having a central blank portion provided with a slot, a needle adapted for the playing of the record occupying the slot and means for retaining

the needle in the slot and protecting it from moisture.

5. A phonograph record disk comprising a paper base having therein a slot and a lacquer record surface, and a needle occupying said slot and adapted for use in playing a record formed on the disk, the needle being retained in position and protected from moisture by a small quantity of lacquer.

10 6. A phonograph record disk having means for holding a stylus adapted for use in the reproduction of the record.

15 7. A phonograph record disk having means at a portion thereof not used for the record for holding a stylus adapted for use in the reproduction of the record.

20 8. A phonograph record disk having means adapted to receive and hold a reproducing stylus adapted for use in the reproduction of the record.

25 9. A phonograph record disk provided with an opening in the material composing the disk adapted to receive and hold a stylus adapted for use in the reproduction of the record on the disk.

30 10. A phonograph record disk provided with an opening in the material composing the disk adapted to receive a recording stylus and means for securing the stylus in said

35 opening.

11. A phonograph record disk provided with an opening in the material composing the disk adapted to receive a recording stylus and means for retaining the stylus in the

opening and for protecting it from moisture.

In witness whereof, I have hereto set my hand this 17th day of January, 1930.

PAUL J. SCHWARZHAUPT.
